(57) **CLAIM**

The ornamental design for a bottle, as shown and described.

DESCRIPTION

FIG. 1 is a top, front right side perspective view of a bottle, showing our new design;
 FIG. 2 is a left side elevational view thereof;
 FIG. 3 is top plan view thereof;
 FIG. 4 is a front elevational view thereof;
 FIG. 5 is a bottom plan view thereof;
 FIG. 6 is a right side elevation view thereof; and,
 FIG. 7 is a rear elevational view thereof.
 The broken lines in the figures illustrate the portions of the design that form no part of the claimed design.
